FOLDING CARTON

William R. Saidel, Green Bay, Wis.

Application March 18, 1949, Serial No. 82,221

5 Claims. (Cl. 229—27)

1

This invention relates to improvements in folding cartons and it consists of the matters herein illustrated and described and more particularly pointed out in the appended claims.

One of the objects of the invention is to provide a carton which can be produced from a one piece paper board blank, cut and scored to form the bottom, the top and the two sides of the carton and which blank may be easily manipulated from its flat folded condition to its set up condition and wherein parts of the top are turned downwardly into perpendicular positions to form the ends and transverse partitions that divide the carton into side by side commodity receiving compartments.

Another object of the invention is to provide a carton of this kind in which there is no waste of the paper board of which it is made and in which the commodity is advantageously displayed to view from not only the entire top of the carton but also from parts of the sides therefor.

A further object of the invention is to provide a carton of this kind which when filled and stacked, the one upon the other, ably withstands the load pressure of the cartons above without crushing and without damage to commodities within the compartments of the cartons.

Also it is an object of the invention to provide, in a carton of this kind, a novel arrangement of parts for the bottom and for at least the ends of the carton and wherein the ends of the cartons are held against displacement by certain of said parts of the bottom when the carton is in its set up condition ready to receive the commodity in the compartments thereof.

Again it is an object of the invention to provide a transversely partitioned carton with side by side compartments which can be produced with a considerable saving in paper board and labor over that required for similar cartons as heretofore devised and with a corresponding reduction in the cost of manufacture without a sacrifice in the strength of the carton.

The above mentioned objects of the invention as well as others, together with the advantages thereof will more appear as the specifications proceeds.

In the drawings:

Fig. 1 is a perspective view of a folding, one piece paper board carton embodying the preferred form of the invention, in its set up, ready to use condition.

Fig. 2 is a longitudinal vertical sectional view through the improved carton as taken on the line 2—2 of Fig. 1.

2

Figs. 3 and 4 are transverse vertical sectional views through the carton as taken on the lines 3—3 and 4—4 respectively of Fig. 2 and on a scale enlarged over that of Fig. 2.

Fig. 5 is a top plan view of the carton in its folded condition, known as a "sleeve."

Fig. 6 is an end view of the carton when in the folded "sleeve" condition of Fig. 5, the dot and dash lines indicating its open condition.

Fig. 7 is a bottom plan view of the carton when in its folded "sleeve" condition.

Fig. 8 is a plan view of a one-piece cut and scored paper board blank, from which the improved carton is made.

Fig. 9 is a fragmentary detail perspective view on an enlarged scale of parts of the carton toward one end thereof when in the set-up condition of Fig. 1 and which will be more fully referred to later.

Fig. 10 is a fragmentary vertical sectional view through parts of the carton appearing in Fig. 9, as taken on the line 10—10 thereof.

Fig. 11 is a detail view in elevation, on an enlarged scale, of a portion of the blank of Fig. 8 within the dash and dot line rectangle 11a thereon and more clearly shows certain "nicks" at the intersections of some of the cut lines and scored lines in the blank, and which will be mentioned in more detail later.

In general the improved folding carton is made from a one piece cut and scored blank of paper board such as free bending chip board, bleached manila board, lined board, patent coated board, laminated board stock with grease proof sheeting or the like.

Such a blank, which is of generally rectangular shape, includes laterally spaced parallel score lines which extend in one direction of the blank to divide the blank into panels, which form the sides, the top and the bottom of the carton when in partly set up condition. The mid panel and parts of the side panels are cut and scored into sections which when turned downwardly into a perpendicular position, form both ends for and one or more partitions in the fully set up carton that divide the same into side by side commodity receiving compartments.

Referring now in detail to that embodiment of the invention illustrated in the drawings, Fig. 8 shows the blank from which a carton such as shown in Fig. 1 is made.

Said blank is substantially rectangular in shape and it is provided with a pair of cut-scored lines 10 and 11 respectively and spaced equal distances 55 inwardly from and parallel with said lines are

3

other cut through lines 12, and 13, and score lines 12a and 13a respectively. That part of the blank between the lines 12, 12a and 13, 13a respectively forms a mid panel 14, which ultimately becomes the open top of the carton, those parts of the blank between the lines 10 and 12, 12a and between the lines 11 and 13, 13a form the two side panels 15—15 of the carton and those parts of the blank outwardly of the lines 10 and 11 form two end panels 16 and 17 respectively that make up the bottom of the carton.

The mid panel 14 is cut transversely along lines 18, 18x, 19, 20 and 21 respectively. The lines 18, 18x, 20 and 21 terminate substantially at the cut and scored lines 12, 12a and 13, 13a while the line 19 extends beyond said last mentioned lines as appears in Fig. 8, except for a slight interruption for a purpose hereinafter mentioned. It is pointed out that the cut lines mentioned do not actually meet or cross the cut and scored lines 12, 12a and 13, 13a respectively, but stop short thereof to leave portions 12x and 13x respectively, known as "nicks" and by which parts adjacent said lines are held together against displacement while the blank is being folded by machine into sleeve form, as will be later mentioned, and at which time said "nicks" readily break at least partway through. In Fig. 11, the "nicks" 13x are indicated by dotted line circles, better to illustrate their presence, but it is to be understood that such circles are not present upon the blank. While these "nicks" are desirable and helpful, they may be omitted, in which event the lines would actually meet. But with the "nick" present, there is less danger of the parts opening up prematurely whilst the box structure is in the process of manufacture. The mid panel 14 is provided with transverse lines 22 and 23 of longitudinally spaced perforations which facilitate bending of the parts upon opposite sides thereof into right angled relation. These lines of perforations terminate at the lines 12, 12a and 13, 13a. The cut and scored lines mentioned divide the center panel of the blank into two end sections 24 and 25 and intermediate sections 26, 27, 28, 28a and 29 respectively which, in the set-up carton, form the two ends and five partitions for the carton, as best appears in Fig. 1. The end sections 24 and 25, along with the intermediate sections 26, 27 and 29, have flange-like tabs 24a, 25a, 26a, 27a and 29a respectively, joined thereto by the transverse score lines 22 and 23 respectively.

The ends of the sections 24, 25, 26, 27, 28 and 29 are defined by certain of the scored lines 12a and 13a, before mentioned and the ends of the flange-like tabs 24a, 25a, 26a, 27a and 29a are defined by the cut lines 12 and 13, before mentioned.

At each end of the sections 24, 25, 26, 27, 28 and 29 respectively are wing extensions 30, 31, 32, 33, 34 and 35 respectively, joined to the said sections by the scored lines 12a and 13a. The wing extensions mentioned, which are partially cut from the panels 15, 15, are of generally triangular shape, with truncated tops, the bases being considered as formed by the score lines 12a and 13a respectively.

By this arrangement of sections 30 to 35 inclusive, there are defined between them, triangularly shaped portions 38, the apexes of which terminate substantially in the planes of the lines 12, 12a and 13, 13a respectively. In the finished carton these portions 38 are disposed at the top of the side walls thereof as formed by the panels 15 and 16 and each portion 38 has a score line 39 about midway the apex and the base thereof, the

4

purpose of which will appear later. It is pointed out that at each end of the panels 15 and 16 are portions 38a arranged in line with but of half the size and shape of the portions 38. Said portions 38a are formed with score lines 39a similar to and in line with the score lines 39 and the purpose of said score lines 39 and 39a is to afford an outward expansion of the panels 15—15.

In each of the wing extensions 30, 31, 32, 33 and 35 are short lines of longitudinally spaced perforations 22a, 22a, 22a and 23a, 23a respectively that are parallel with but offset from the associated lines of spaced perforations 22 and 23 by an amount slightly more than the thickness of the stock of the blank and thus there is defined in each of these extensions a triangular tab 40.

The panels 16 and 17 of the blank are each of a width greater than one-half the width of the mid panel section 14. Parts of the free margin of the panel 16 are cut away to provide longitudinally spaced tabs 41 and parts of the free margin of the panel 17 are cut away to form recesses 42 which are disposed in alignment with and are the same in area as the tabs 41. One of the lateral edges of these recesses 42 form stop shoulders for engagement by the edges of the flanges 24a, 25a, 26a, 27a and 29a when the blank is set up into the carton form, as in Fig. 1. With the arrangement of the tabs 41 and recesses 42, as shown in Fig. 8 and as before described, the tabs on the panel 16 are formed from those parts of the paper board strip from which the blank is made, cut from the panel 17 to form said recesses 42. Thus, there is no waste of stock in the production of successive blanks from a strip of paper board stock.

On that face of the free margin of the panel 16, which is the inner face in the set-up box, is a band of adhesive outwardly of the dash and dot line 43 (see Fig. 8) and this band of adhesive also covers the corresponding side of the tabs 41.

In Figs. 5, 6 and 7 are shown top, end and bottom views of the blank of Fig. 8 when folded into its collapsed or knocked-down "sleeve" condition and in which condition they will stack flatwise for shipment and storage. To bring the blank to this condition, the panel 17 is folded along the line 11 into overlapping relation upon the center panel and then the panel 16 is folded over upon the panel 17 and united thereto by the adhesive, before mentioned. The blank is then in its flat folded or "sleeve" condition, as shown in Figs. 5, 6 and 7. This folding of the blank into sleeve form is performed by a blank folding machine and it is in this folding operation that the "nicks" 12x and 13x are broken at least partway through on the 180° folded side after being mechanically fed from the hopper of said machine, at which time said "nicks" have served their purpose. Considering the blank in this flat folded condition with the panels 14 and 15 facing upwardly, as in Figs. 5 and 6, this disposes the scored lines 12 and 11 at opposite edges of the flat folded blank, as in Fig. 6.

To manually open up the flat folded blank of Figs. 5, 6 and 7, it is only necessary to grasp the side edges thereof as now defined by lines 11 and 12, between the fingers, and exert inward pressure on said edges as in Fig. 6, whereupon the blank opens up into the extended position shown in dot and dash lines in Fig. 6, the upward swing of the panels in this operation being indicated by the arcuate arrows of Fig. 6. It is in this part of the hand operation of setting up the sleeve

that the remaining part of the "nicks" are broken through completely from their other side.

When the carton has been thus far set up and it is desired to complete the same by hand operations, the various sections are manipulated to dispose them in the partition forming arrangement shown in Figs. 1 and 2. As the manipulation for each of said sections is generally the same, a detailed description of the manipulation of one will suffice for all and in this instance the section 26 is chosen as an example.

Start by placing the thumbs in the sleeve and toward the bottom thereof, bearing against the inside surfaces of the side walls 15-15. Then press the walls slightly outward. This causes an inward bending along lines 39 so that the triangular apex portions of the parts 38 point inwardly and approach toward the horizontal. Due to this action the tabs 32, which are connected to the apex portions along the lines 37 swing upwardly and outwardly, thus extending beyond the bottom part of the side walls. With the parts in position, downward finger pressure is imposed upon the section 26, near its flange 26a. The tabs 32 swinging on the score line 12a-13a turn upwardly, as they start to swing inside the side walls 15-15. Continued downward movement of the section 26 causes the flange 26a to engage the bottom of the carton and as the section 26 is swung to its vertical position, causes the flange 26a to be bent at right angles to the part 26. By the time the part 26 has reached a perpendicular position the tabs 32 will have been disposed against the inner surfaces of the respective side walls 15-15 and the tabs 40-40 will have been disposed on top of the flange 26a, as best shown in Fig. 9. The score lines 22a are offset from the score line 22 to facilitate the disposition of the tabs 40 on top of the flange 26a, as just described.

When said section 26 is in its upright position, its flange 26a will engage flatwise upon the bottom (as formed by the panels 16 and 17) and a part of the free edge of said flange is engaged with one of the lateral edges of an associated recess 42 in the panel 17. Thus an end portion of the flange 26a will engage directly upon a part of the panel 16 and the other end portion of the flange will engage directly upon a part of the panel 17. A part of this flange between said end portions in the manipulation mentioned will assume an inclined position, thus permitting the end portions to lie in different levels wherein the intermediate part of the edge of said flange will abut the lateral shoulder formed by an edge of the associated recess 42.

This arrangement or location of the parts are best shown with respect to the flange 24a of the end section 24 in Fig. 9.

The sections 24, 25, 27 and 29 are manipulated in the same way as that described in connection with the section 26, the sections 24 and 25 forming the ends of the carton.

It will be understood that in manipulating sections 24, 26, 27 and one of the sections 28a, the operator will hold the sleeve with the section 24 nearest to him. By first manipulating section 24, the other sections 26, 27 and one of the sections 28a can be taken in order, since the thumbs of the operator can be inserted from above through open space between the first completely manipulated section and the next adjacent but unmanipulated section of the sleeve.

To manipulate sections 25, 29 and the other section 28a, the carton is reversed, end for end,

so that the section 25 is closest to the operator. This permits manipulation in the manner before described.

As the sections 24 and 25 are swung downwardly along the fold lines 37, the portion 38a will bend automatically along the fold or score lines 39a. By the provision of the fold or score lines 39, 39a, it has been found that either in the setting up of the sleeve into carton form by hand or by semiautomatic machines employing jigs, said score lines are indeed practical in affording a uniform outward expanding of the sides of the set up carton.

In the manipulation of parts 28a-28a of the section 28, they swing downwardly in opposite directions and as each part 28a is of a width less than the depth of the carton, the bottom edges of said parts will be disposed above the bottom of the carton, as appears in Figs. 1 and 2.

It is to be noted especially from Figs. 2 and 9 that the extensions 30 to 35 inclusive provide a double thickness of paper board for each side wall and in connection with the respective sections 24 to 29 inclusively, tie said double thicknesses of paper board together, thus producing along each side, parts of angle bars cross section capable of withstanding heavy vertical compression loads without yielding or buckling.

Thus, the filled cartons when stacked, one upon the other, will amply protect the contents of the carton without damage due to the weight of the filled cartons above.

When the carton is in its completely set-up condition, as appears in Fig. 1, the spaces in the side walls left by the wing extensions 30 to 35 inclusive are symmetrically spaced apart and adjacent spaces are separated by symmetrical parts as formed by the triangular portions 38 of said side walls.

It is pointed out that in the completely set-up cartons, parts of these portions 38 adjacent the fold lines 39 protrude or bulge slightly outwardly from the remainder of the side wall and do not lie flat against the portions 30 to 35 inclusive. Thus said parts of said portions act as cushions to absorb lateral shock for adjacent cartons on each side thereof and this affords further protection for the contents of the carton, which contents are often in themselves of an easily broken or damaged character.

It will also be noted that an edge of each tab 40 engages the vertical face of the adjacent full section. This aids in strengthening the structure.

Cartons of this kind, when containing the desired commodities, are generally wrapped in a transparent film-like sheeting and when the improved carton herein is so wrapped, it presents a neat and attractive appearance and a good and sanitary display of the commodity.

A carton made in accordance with the above may be produced from a blank which does not require a waste of the stock of which the blank is formed. In its set-up condition, as shown in Fig. 1, the partitions materially strengthen the carton and permit a stacking of the filled cartons, one upon the other, in a manner withstanding considerable load pressure of the filled cartons above, thus permitting stacking.

The partitions mentioned also serve the purpose of holding the two sides of the completed carton perpendicularly to the bottom and against bellying or bowing outwardly before wrapping the filled carton in a paper sheet or the like. Thus the necessity of tying a string or cord

around the filled carton before wrapping the same is eliminated. As said partitions are integral parts of the carton itself and are joined or connected to the sides of the carton in the manner described, they afford a full visibility to each compartment between said partitions.

Portions of the cut lines 36 are disposed at an angle of forty-five degrees to parts forming the top edges of the sides of the carton. This permits and facilitates folding of the end and partition members or sections from the horizontal position which they occupy when the carton is in the partly assembled form shown by dot and dash lines in Fig. 6 to the completed form in which the end and partition members or sections are vertically disposed.

While in describing the invention, I have referred in detail to form, construction and arrangement of the various parts of the carton, the same is to be considered only in its illustrative sense and therefore I do not wish to be limited thereto except as may be specifically set forth in the appended claims.

I claim as my invention:

1. A blank for a carton of the kind described embodying therein a rectangular piece of paper board material including a central panel, a panel at each side of and joined to the central panel by a cut and scored line and at least a fourth panel joined to one of the side panels by a scored line, said central panel having transverse cut and scored lines terminating at said first mentioned cut and scored lines and dividing the same into sections, each having truncated triangular full width wings at their ends cut from each side panel and foldably joined thereto by parts of said cut and scored lines between said central and said side panels, each wing having converging side edges, parts of each of said wings being joined to parts of each side panel by scored lines included in one side edge of each wing.

2. A blank for a carton of the kind described embodying therein a rectangular piece of paper board material formed to provide a central panel, a panel at each side of and joined to said central panel by fold lines and a fourth panel joined to at least one of said side panels, the opposite ends of all of said panels providing continuous straight line edges for opposite ends of the blank, said central panel being divided transversely into end and intermediate sections, the opposite end edges of said end sections being coincident with and forming parts of the end edges of the blank, each end and intermediate sections having truncated triangular wings at their opposite sides, each cut from an associated side panel and each joined at its base thereto along said first mentioned fold lines and having oppositely inwardly angled side edges and a free end edge parallel with the base thereof, a part of at least one angled edge of each wing being joined to the associated side panel by a fold line beginning at the first mentioned line and terminating short of the free edge of said wing.

3. A blank for a carton of the kind described embodying therein a rectangular piece of paper board material formed to provide a central panel, a panel at each side of and joined to said central panel by fold lines and a fourth panel joined to at least one of said side panels, the opposite ends of all of said panels providing continuous straight line edges for opposite ends of the blank, said central panel being divided transversely into end and intermediate sections, the opposite end edges

of said end sections being coincident with and forming parts of the end edges of the blank, each end and intermediate sections having truncated triangular wings at their opposite sides, each cut from an associated side panel and each joined at its base thereto along said first mentioned fold lines and having oppositely inwardly angled side edges and a free end edge parallel with the base thereof, a part of at least one angled edge of each wing being joined to the associated side panel by a fold line beginning at the first mentioned line and terminating short of the free edge of said wing, and a score line in each part of each side panel and arranged parallel with the first mentioned fold line and extending between the oppositely angled edges of adjacent wings.

4. A blank for a carton of the kind described embodying therein a rectangular piece of paper board material formed to provide a central panel, a panel at each side of and joined to said central panel by fold lines and a fourth panel joined to at least one of said side panels, the opposite ends of all of said panels providing continuous straight line edges for opposite ends of the blank, said central panel being divided transversely into end and intermediate sections, the opposite end edges of said end sections being coincident with and forming parts of the end edges of the blank, each end and intermediate sections having truncated triangular wings at their opposite sides, each cut from an associated side panel and each joined at its base thereto along said first mentioned fold lines and having oppositely inwardly angled side edges and a free end edge parallel with the base thereof, a part of at least one angled edge of each wing being joined to the associated side panel by a fold line beginning at the first mentioned line and terminating short of the free edge of said wing, and a score line in each part of each side panel and arranged parallel with the first mentioned fold line and extending between the oppositely angled edges of adjacent wings in the plane of the outer end of that part of said fold line in said side panel that joins the wing to said side panel.

5. A blank for a carton of the kind described embodying therein a rectangular piece of paper board material formed to provide a central panel, a panel at each side of and joined to said central panel by fold lines and a fourth panel joined to at least one of said side panels, the opposite ends of all of said panels providing continuous straight line edges for opposite ends of the blank, said central panel being divided transversely into end and intermediate sections, the opposite end edges of said end sections being coincident with and forming parts of the end edges of the blank, each end and intermediate sections having truncated triangular wings at their opposite sides, each cut from an associated end panel and each joined at its base thereto along said first mentioned fold lines and having oppositely inwardly angled side edges and a free end edge parallel with the base thereof, a part of at least one angled edge of each wing being joined to the associated side panel by a fold line beginning at the first mentioned line and terminating short of the free edge of said wing, at least certain of said sections including a fold line, the ends of which terminate at said first mentioned fold lines and provide bendable flanges for the associated section, each wing of said certain of said sections having a fold line therein substantially in line with the fold line in the associated section, there being a slit in each 75 of the first mentioned fold ends in line with and

9

of a length approximating the width of said bendable flange.
